CLAIM

The ornamental design for a window de-icer, as shown and described.

DESCRIPTION

FIG. 1 shows a perspective view of the window de-icer; FIG. 2 shows a front view thereof;

FIG. 3 shows a rear view thereof;

FIG. 4 shows a right side view thereof;

FIG. 5 shows a left side view thereof;

FIG. 6 shows a top plan view thereof; and,

FIG. 7 shows a bottom plan view thereof.

The broken line showing of portions of the window de-icer is included for the purpose of illustrating portion of the article that forms no part of the claimed design.

1 Claim, 5 Drawing Sheets(56)
